COIN CONTAINER

Hildaur L. Neilsen, Metuchen, N. J.

Application September 22, 1950, Serial No. 186,168

3 Claims. (Cl. 206—0.83)

1

This invention relates to a coin container for holding equal groups of coins in axial alignment in such a manner as to facilitate rapid counting thereof.

Where large quantities of change money are handled it is common practice to count a certain number of coins of each denomination and wrap a stack of them in individual envelopes. In this way the coins are contained in a compact package and may thereafter be transported more conveniently and counted or deposited in a bank with greater facility. Generally it is a nuisance for one to count each coin and then wrap them, and of course the wrappers must be removed if accurate verification is required.

Accordingly, it is an object of this invention to provide a coin container which holds a predetermined number of coins and which eliminates need for wrapping. A further object is to provide an easily loadable device for holding coins in stacked relationship, and which is transparent or open along a side so that the coins can be counted without opening the container. A still further object is to provide a coin container having a plurality of compartments to subdivide a stack of coins into small equal groups for easy loading and counting, and which permits visual inspection of the money contained therein when the container is closed. Another object is to supply a device of the type described that is inexpensive to produce, easy to handle, and of sturdy construction to permit repeated use. Still a further object is to provide a coin container with a compartmented transparent plastic case on which is slidably mounted a curved lid useful for aiding the loading operation or wrapping of coins in a paper wrapper if this is desired. These and other objects will be apparent from the description which follows.

The invention accordingly comprises the features of construction, combination of elements, and arrangement of parts, which will be exemplified in the construction hereinafter set forth, and the scope of the invention will be indicated in the claims.

For a fuller understanding of the nature and objects of the invention reference should be had to the following detailed description taken in connection with the accompanying drawing, in which:

Fig. 1 is a perspective view of a coin container with the lid half removed and partially cut away in front;

Fig. 2 is an enlarged front elevation, partially in section, of the coin container shown in Fig. 1, with the lid in place;

Fig. 3 is a view taken along line 3—3 of Fig. 2; and

Fig. 4 is a perspective view of the lid being used as a cradle for transferring a stack of coins to a paper wrapper.

Similar reference characters refer to the same

2

parts throughout the several views of the drawings.

In accordance with one embodiment of the invention, there is provided a container to hold 5 fifty pennies for example, comprising a transparent plastic box, having the general shape of a right isosceles triangle in transverse section, and a slidably mounted convex lid therefor. The inside of the box is subdivided preferably into ten compartments of equal width to hold five coins 10 in each compartment and a narrow rail is disposed along one longitudinal edge to cover a portion of each compartment and prevent coins rolling out of the box as it is being loaded. The lid encircles the open part of the box and fits around the outside of each edge to be retained and guided thereby, and one end is provided with stops to limit movement to the closed position. A small bead may also be provided to engage a dimple in the box to snap-lock the lid when closed.

A compact unit to hold fifty coins is thus provided, having a transparent box portion allowing 20 visual inspection of the contents. Each compartment is defined by a partition on each side 25 leaving an opening which is wider than four coins but of less width than six, so that no more than five coins can be placed therein, thus preventing errors; since the stack is subdivided, counting can be accomplished by a mere glance as any 30 group of less than five coins is readily discernible. The partitions therefore separate successive groups of coins to permit rapid counting, and they are cut away to provide easy access to any individual group.

The design of the lid makes it particularly useful 35 as a cradle for a stack of coins, because the stack may be placed within the hollow of the lid and parcelled out when loading the box portion, or if wrapping is to be done, the wrapping paper 40 can be positioned underneath and rolled around the coins as they are held in the lid. If a cylindrical paper wrapper is employed, the lid serves as a funnel for transferring a stack of coins into the wrapper.

Accordingly, a small, handy container is provided 45 by this invention to hold a fixed number of coins in such fashion as to permit rapid verification.

Referring now to the drawings: an elongated 50 transparent plastic box 10 (Fig. 1) has partitions 12 to subdivide it preferably into ten equal coin compartments 14 that can hold no more than five coins each. Partitions 12 have cut-away edges 16, above which coins 18 project (as 55 shown in broken lines in Fig. 3), and which, with side walls 20 and 22, create substantially right isosceles triangular sections. Partitions 12a and 12b are disposed adjacent end walls 13a and 13b respectively; and so each compartment 14 is defined by two such partitions and is displaced a substantially equal distance from the adjacent 60 end wall or group of coins (Figs. 1 and 2). This

arrangement separates coins into equal groups, causes counting to be facilitated because of such separation, and makes each group readily accessible for removal from box 10.

A rail 26 along the front edge of wall 22 restrains coins from rolling out, while a generally similar rail 24 at the top of wall 20 serves the same purpose when box 10 is tilted backwards. Rails 24 and 26 in addition serve as stiffeners for walls 20 and 22 respectively, and brace partitions 12.

An elongated lid 28 has flanged edges 30 and 32 to engage the exposed edges of walls 20 and 22 respectively, and a concave body portion 34 which encloses the open part of box 10 when lid 28 is in place. Stops 36 are disposed at one end to limit movement to closed position (Fig. 2), and a suitable catch or ball 38a and dimple 38b are provided to snap-lock the lid in closed position (Fig. 1).

Preferably the side walls 28c and 28d (Fig. 3) of lid 28 lie in planes that are at right angles. Thus when the lid is closed the container has a generally square cross section which facilitates stacking a number of the containers.

A coin container according to this invention may of course be made for any denomination by varying its dimensions. The one described is for pennies and is designed to be loaded manually, as from the loose change drawer in a cash register, to a capacity of fifty coins—the amount generally contained in paper wrappers such as used by banks. One using box 10 with lid 28 has a handy container that is easily filled and which makes counting unnecessary, since the size of compartments 14 predetermines the number of coins that can be placed in box 10, though segregation of the stack of fifty pennies into ten groups of five each greatly facilitates counting. If box 10 is made of transparent material, or if an opening (not shown) is placed along the side, then, of course, counting is accomplished even when lid 28 is in place.

It is convenient to transport coins in box 10 and use it when storing money for safekeeping, or when distributing it to others, and individual counting of coins to verify cash received is unnecessary. However, there may be times when wrapping is desirable, in which case lid 28 is of great use, as illustrated in Fig. 4. A simple procedure is first to stack fifty coins in box 10 as explained, and then to dump the entire stack onto concave side 28a of lid 28 (when removed from box 10) while holding the lid with stops 36 positioned at the bottom; a paper wrapper 40 is next held near upper edge 28b of lid 28 and when the two are tilted in the opposite direction lid 28 serves as a cradle for the stack of pennies 42 and the coins slide into envelope 40 while maintaining their stacked relationship. This procedure is particularly efficient because handling and counting of coins are minimized during wrapping.

Dispensing of coins from box 10 is also greatly facilitated by lid 28. It is seldom necessary or desirable, in making change, to dispense more than four coins. For example, if it is desired to dispense three coins, the box may be held in approximately the Figure 1 position with the left end higher than the right and lid 28 slid back until three coins are exposed. The box may then be rotated about its axis and the desired number of coins will drop out. The lid may then be closed and the remaining coins are locked in the box.

There is thus provided by this invention a sturdy, inexpensive coin box that attains the several objects hereinabove in thoroughly practical and efficient manner.

Since certain changes may be made in the above embodiment and different embodiments of the invention could be made without departing from the scope hereof, it is intended that all matter contained in the above description or shown in the accompanying drawing shall be interpreted as illustrative and not in a limiting sense.

Having described the invention, what is claimed as new is:

1. A coin container comprising, in combination, an elongated body portion having a pair only of flat sides at least one of which is formed of transparent material, said sides being secured together and extending from one another with one side forming the bottom of said container and the other the rear wall thereof, the width of said walls substantially equaling the diameter of the coin to be contained whereby when said container is resting on its bottom its body portion is freely accessible for insertion or removal of coins in planes lying at right angles to one another, a plurality of partitions in said body portion subdividing it into coin receiving compartments, and a lid slidably mounted on said body portion.

2. A coin container comprising, in combination, an elongated body portion having a pair only of flat sides at least one of which is formed of transparent material, said sides being secured together and extending from one another in planes lying at right angles to one another, a plurality of partitions in said body portion subdividing it into coin receiving compartments, and a lid slidably mounted on said body portion, said lid being generally convex and including flanges respectively at its edges to engage portions of said body portion sides so that the lid when in closed position is retained therein, the radius of convexity of said lid being substantially the same as that of the coin to be contained.

3. A coin container comprising, in combination, an elongated body portion having a pair only of flat sides at least one of which is formed of transparent material, said sides being secured together and extending from one another in planes lying at right angles to one another, a plurality of partitions in said body portion subdividing it into coin receiving compartments, a rail secured to one of said sides and extending outwardly therefrom to preclude coins rolling out of said body portion when said container is resting on said last-mentioned side, and a lid slidably mounted on said body portion.

HILDAUR L. NEILSEN.
